(57) **CLAIM**

The ornamental design for a set of fuses as shown and described.

DESCRIPTION

1. Set of fuses
- 1.1 : Perspective
- 1.2 : Perspective
- 1.3 : Front
- 1.4 : Back
- 1.5 : Top
- 1.6 : Bottom
- 1.7 : Right
- 1.8 : Left
- 1.9 : Cross sectional taken along line 1.9 and 1.9 in FIG. 1.3
